HETERO CYCLIC HYDROXY COMPOUNDS

Ernst Herdieckerhoff, Opladen, near Cologne, and
 Eduard Tschunkur, Cologne-Mulheim, Germany, assignors to I. G. Farbenindustrie Aktiengesellschaft, Frankfort-on-the-Main, Germany

No Drawing. Application October 5, 1934, Serial No. 747,090. In Germany October 12, 1933

4 Claims. (Cl. 260—44)

The present invention relates to a process for the manufacture of heterocyclic hydroxy compounds, more particularly it relates to compounds which may be represented by the probable general formula:

10 wherein x stands for sulfur or oxygen.

In accordance with the present invention heterocyclic hydroxy compounds of the above identified formula are prepared by starting with a sulfonic acid of the general formula:

20 wherein x means the same as stated above, or a salt thereof, especially a water soluble salt, such as an alkali metal salt, and treating the same with a saponifying agent. The reaction proceeds in such a manner that the sulfonic acid group is saponified with a splitting off of sulfurous acid. 25 As saponifying agents suitable for carrying out the process there come into consideration all the agents known in the art for performing saponification; for example, there can be used acid saponifying agents, such as diluted aqueous mineral acids, for example, hydrochloric acid, sulfuric acid, phosphoric acid and the like, further acid salts, such as bisulfate and the like. Likewise the process can be performed with the aid of an alkaline saponifying agent, dilute aqueous caustic soda lye or aqueous caustic potassium lye being enumerated by way of example.

30 The conditions of working, i. e. temperature and concentration of the saponifying agent, depend to a high degree on the specific heterocyclic sulfonic acid which is subjected to the reaction and to the specific saponifying agent used. Thus, for example, when subjecting an oxazole-2-sulfonic acid to our new process, there can be generally applied moderate conditions, while in case 35 of thiazole sulfonic acids generally stronger conditions, such as the application of an aqueous mineral acid, say of about 1 to 5% strength, and higher temperatures, say between about 50 and 40 about 100° C., are preferable. Quite generally, when using strong saponifying agents, such as dilute aqueous mineral acids, say of from about 1 to about 5% strength, the saponification can be performed at lower temperatures, in some 45 cases even at normal temperature, while weaker

saponifying agents, such as dilute phosphoric acid or dilute aqueous alkalies, such as dilute aqueous caustic soda lye or dilute aqueous caustic potassium lye, say from 1-10% strength, generally require higher temperatures, say from 5 about 50° to about 100° C. It is to be understood that the statements hereinbefore made with regard to the concentration and temperature are in no way limitative and that the conditions of working may be varied in any suitable manner 10 without departing from the spirit of our invention.

15 The sulfonic acids used as starting components in our invention are obtainable, for example, according to the process described in the application for Letters Patent Serial No. 723,611, filed May 2, 1934 and having the title "Heterocyclic sulfonic acids and process of making same", by reacting upon the corresponding 2-mercapto derivatives, favorably in an alkaline medium, with 20 an oxidizing agent in a quantity corresponding to at least 3 atoms of active oxygen for each atom of the 2-mercapto derivative. Further these sulfonic acids are obtainable by reacting upon compounds of the formula:

25 wherein x means the same as stated above, with a sulfite.

30 It is self-understood that in performing our new process it is not necessary to start with the isolated sulfonic acids, but the same can be directly saponified in the reaction mixtures resulting from their process of manufacture.

35 The invention is illustrated by the following examples, without being limited thereto:

Example 1.—50 kgs. of the sodium salt of benzoxazole-2-sulfonic acid are dissolved in 40 300-400 litres of warm water, and the solution is weakly acidified with hydrochloric acid. The 2-hydroxybenzoxazole having the following formula:

45 of the melting point 140° C. separates in a good 50 yield with splitting off of sulfurous acid.

Example 2.—50 kgs. of the sodium salt of β -naphthoxazole-2-sulfonic acid are dissolved in about 300 litres of warm water; on acidifying the solution with sulfuric acid, sulfurous acid is 55

split off with formation of 2-hydroxy- β -naphthothiazole of the formula: 5-chloro-2-hydroxybenzothiazole of the formula:

5

10

of the melting point 206° C. in a good yield.

Example 3.—212 kgs. of 2-mercapto-6-nitrobenzothiazole are dissolved with about 240 kgs. of aqueous caustic soda lye of 50% strength in about 1000 litres of water at 20-30° C., and to the solution there are slowly added, while stirring, 340 kgs. of aqueous hydrogen peroxide solution of 30% strength. Thereby is formed in a rather quantitative yield the sodium salt of the 2-hydroxy-6-nitrobenzothiazole having in the free state the following formula:

25

by splitting off sulfurous acid from the corresponding 2-sulfonic acid which intermediately has formed. After redissolving from aqueous caustic soda lye and salting out with common salt, the sodium salt of 2-hydroxy-6-nitrobenzothiazole is obtained in form of yellowish crystals; the free compound shows the melting point 252° C.

35 In an analogous manner there is prepared the 2-hydroxy-5-nitrobenzothiazole of the melting point 282° C.

Example 4.—40 kgs. of 2-mercapto-benzothiazole are dissolved with 25 kgs. of aqueous caustic soda lye of 50% strength in 100 litres of water, and at 20-30° C. there is slowly added a solution of 80 kgs. of potassium permanganate in about 800 litres of water. After this the reaction mixture is heated to 80-90° C., and the manganese sludge formed is filtered off. The filtrate containing the benzothiazole-2-sulfonic acid is rendered acid to congo with hydrochloric acid, while hot, whereupon the bulk of the 2-hydroxybenzothiazole separates directly with a strong development of SO₂. A further quantity of the 2-hydroxybenzothiazole crystallizes on cooling. The output is about 90% of theory. The product having the following formula:

55

is very pure and shows the melting point of 60 138° C.

The process can also be performed at other temperatures between about 50 and about 100° C.

In an analogous manner there are prepared from the corresponding benzothiazole-2-sulfonic acids or naphthothiazole-2-sulfonic acids respectively:

4-chloro-2-hydroxybenzothiazole of the formula:

70

of the melting point 204-205° C.

5

of the melting point 218° C. 6-methoxy-2-hydroxybenzothiazole of the formula:

10

of the melting point 163-164° C. 2-hydroxy- α -naphthothiazole of the formula:

15

of the melting point 287-288° C. 2-hydroxy- β -naphthothiazole of the formula:

20

of the melting point 235° C.

The 2-hydroxyarylene compounds obtainable in accordance with the new process can be used as intermediate products for the manufacture of synthetic drugs and other technically valuable substances.

We claim:

1. The process of preparing a compound of the group consisting of 2-hydroxyoxazoles and 2-hydroxythiazoles which comprises splitting off 45 sulfurous acid from a compound of the general formula:

30

wherein ar stands for an arylene radical of the benzene or naphthalene series, x stands for a member of the group consisting of sulfur and oxygen, and y stands for a member of the group consisting of hydrogen and a monovalent metallic radical, by treating with an acid saponifying agent.

2. A process as claimed in claim 1, in which a dilute aqueous mineral acid is used as saponifying agent.

3. The process of preparing 2-hydroxyoxazole which comprises treating oxazole-2-sulfonic acid with dilute aqueous hydrochloric acid at normal temperature.

4. The process of preparing 2-hydroxybenzothiazole which comprises treating benzothiazole-2-sulfonic acid with dilute aqueous hydrochloric acid at a temperature between about 50 and about 100° C.
